OTTO WOLTERS, OF MAGDEBURG, AND HEINRICH DREWELL, OF CHARLOTTENBURG, GERMANY, ASSIGNEES TO OTTO WOLTERS, OF MAGDEBURG, GERMANY.

COMPOSING PUNCHING MACHINE FOR THE PRODUCTION OF REGISTERING STRIPS FOR AUTOMATIC TYPE-LINE-CASTING MACHINES.

Application filed June 21, 1924, Serial No. 721,524, and in Germany May 5, 1922.

This invention has for its object to utilize for type line-casting the advantages of the indirect composing method, by means of registering strips which have stood the test for the production of single cast type.

The economical success is in this case even greater than for the single type-casting. An automatic type casting machine operated by means of a registering strip has three times the efficiency of a machine operated by hand.

An additional advantage is, that in this case not only the registering paper strip, the product from the type-punching machine, but also that the cast lines, the product from the casting machine, can be conveyed from place to place and dispatched to any destination.

Factories having only moderate capital can send their registering strips for casting to more important factories which have automatic casting machines, so that they need not invest any capital in casting machines.

Practical automatic apparatus for line-casting machines are known; they are operated by electric contact-closing with the aid of a paper registering strip in which each type is represented by a group of holes, generally two holes. The composing punching machine according to the invention is capable of producing such registering strips.

This small-sized machine, which is easy to transport owing to its light weight, and the driving motor of which can be fed from any lighting main, does not require much space and does not cause any disturbance by radiating heat, smell or noise. The machine is of simple construction and the attendance of the same requires no special mechanical nor composing skill. A special advantage of this machine is that there are no corrections in the registering strips as these corrections are made prior to the punching of the registering strip in the auxiliary line composed of matrix-like elements, said auxiliary line serving for the adjusting of the punching mechanism, executed by the composer by hand in the same simple manner known from composing machines.

Serious disadvantages are thus avoided which are connected with the registering

strip-punching machines in which the depression of the keys of a key board operates the punching mechanism for each type.

The control of the length of the lines is also quite easy, as the measuring mechanism utilizes the advantage that at the line-casting a mechanical compensation is produced by the elastic justifying by wedge spacers. The wedge spacers are represented in the line of elements by rigid elements which are of exactly the same construction as the elements which represent types and signs.

As regards the mechanical composition the composing-punching machine is similar to the well known composing casting machines in which matrices circulate which have V-shaped distributing teeth. Matrix-like elements circulate in the machine which effect the adjusting of the punching mechanism. These elements have no moulds for casting but marks which serve to operate the punching mechanism when they are circulating through the machine. They are of a thickness according to the thickness of the types and fitted with control tokens for the composer.

The circulation of the elements in the machine is carried out in accordance with the proceedings known from the matrix composing machine.

The elements are released from the magazine by depressing keys, juxtaposed in a collector to form a line the length of which is regulated by the measuring mechanism to the accurate length of the line to be composed. The line is raised by an elevator and brought by a feeding slide into the position in which the separating, feeding and distributing take place, by co-operation of the mechanism arranged accordingly, in such close succession that the line which in the meantime has been made ready in the collector can move up immediately without interval.

The efficiency of the machine depends therefore only on the skill of the composer. As the line is formed in the collector from left to right, the punching takes place in inverse direction beginning with the character which has been composed last, the group of

ferred onto the feeding slide which brings the line into the position which is necessary to pass along the separating-feeding- and distributing mechanism, the circulation being thus finished.

The circulation of the elements in the machine and the releasing of the functions of the same in connection therewith produces the following proceedings:

10 By depression of a key, for instance key ^a Fig. 2 of the key board B, the locking pawl 2, which is constructed like an elbow lever and pivotally mounted on pivot pin 3, is disengaged from the draw bar 4. This draw bar 4 is therefore pulled upward by the action of a spring 5 with the result that an escapement 6, the nose 7 of which engages with a notch of the draw bar 4, is drawn along. The elements in the magazine channels are thus released in the well known manner. A lever ^{4a} is hingedly connected by means of a pin ^{4b} with the draw bar 4, its other end being pivotally mounted by means of a pin ^{4c} in a guide slot.

25 Owing to the sudden upward movement of the draw bar 4, when the same is being released by the locking pawl 2, the eccentric ^{4d} is pressed against the rotating rubber cylinder 8 and drawn along by the same whereupon, after one revolution, the draw bar 4 connected with the lever ^{4a} of the eccentric is returned to the zero position so that the locking pawl 2 is brought again in engagement with the draw bar by the action of spring 5 so that it is ready for a new depression of key.

30 The elements are conducted by the conveying band ^{9a} through channel 9, the cover plate of which is omitted in Fig. 1, into the collector D, where they are arranged side by side by the action of a star wheel to form a line.

35 The collector D consists essentially of a guide bar 10 on which the finished line is transported by a collector carriage (Figs. 1 and 3) to the lift. In order to obtain the accurate length of the printing line to be produced indirectly by the elements a measuring mechanism is connected with the collector D, the construction of which is shown in Fig. 3.

An abutment 27 reaching onto the path of the line serves to stop the first element of the line and at the same time to determine the left end of the line, said abutment 27 being adjustably fixed on a plate 12 of the line measuring mechanism by means of a clamping device ^{27a}. The clamping device ^{27a} comprises a pointer 13 indicating on a scale 14 the adjusted length of line in any desired measure, for instance in typographic units or in average width of characters. The plate 12 of the line measuring mechanism carries three adjustable bars 15, 65 16, 17. The bar 15 forms at its upper left

part an abutment which, when the line space is completely filled with elements, strikes against a stop 18 and limits thus the maximum length of the line.

Bar 15 has teeth in its lower edge which gear with a pinion keyed on shaft 19 which is journaled in the plate 12 of the line measuring mechanism. On this shaft 19 a ratchet-wheel 20 is further mounted. A pull spring 21 tends to pull the bar 15 constantly from left to right, this being however prevented by a pawl 22 engaging with the ratchet wheel, said pawl having two teeth. At the state of rest the front tooth engages with the ratchet wheel and locks the same against rotation. When certain keys are struck which, although they release an element must not bring a type element into the line of composed matter so that they do not consume any space in the printed line, the pawl 22 is advanced for one moment so that the rear tooth, which is displaced with regard to the front tooth for about one half of a space between two teeth, engages with the ratchet wheel. This ratchet wheel 20 is thus released so that it is free to execute a rotation equal to one half of a space between two teeth. At the return movement of pawl 22 it oscillates again for the distance equal to one half space between two teeth so that at one to-and-fro movement of the pawl 22 the ratchet wheel 20 rotates for one space between two teeth, the bar 15 moving to the right for an equal distance. As the position of bar 15 indicates the maximum length of the line of elements, this line is lengthened, at every depression of a key which serves for the insertion of a filling element or element which is not to be printed, for a distance which is equal to the thickness of this element, so that the maximum length of the line to be printed is not influenced by the elements. The filling elements are elements which do not serve to control the casting of a type in the type casting machine but merely to control a certain function of the stamping machine, for instance for a sign indicating the end of the line, the reverting to another type magazine and the like.

110 The minimum length of the line is determined by the pointers ^{16a} and ^{17a} on the bars 16 and 17. This minimum length results from the maximum length, which is determined by the bar 15, in that one deducts from it that length which at the justifying of the line is filled either by the spacing by means of the wedge spacers or by blank matrices added to the said wedge spacers. For taking, at the determination of the minimum length, into consideration the space occupied by the filling elements which do not require any printing space, the scale 14 is fixed at ^{14a} on the bar 15 so that scale 14 participates in the shifting of the

bar. The bar 15 carries further a stud 23 on which are rotatably mounted two pinions 24, 25 and a feed wheel 26 with spring barrel 27^b. The pinions 24, 25 and the feed wheel 26 are rigidly connected with one another by a common hub. A spiral spring located in the spring barrel 27 tends to constantly rotate the feed wheel 26 and the pinions 24, 25 and to move from right to left the bars 16, 17 which mesh by means of teeth with the pinions 24, 25 respectively. The rotation of the feed wheel 26 and consequently the movement of the bars 16, 17 is normally prevented by a pawl 26^a having two teeth. At the depression of the wedge spacer- or interval key this pawl is oscillated forward and backward so that at the changing of the engagement of the two teeth of the pawl the wheel 26 is rotated of the width of one tooth. The bars 16 and 17 are moved to the left, the bar 16 approximately double the distance of bar 17 in accordance with the diameter of the pinions. The distance of which the bar 17 is moved corresponds with the space which can be filled by a justifying wedge and the distance of which the bar 16 is removed corresponds to the space which can be filled by a justifying wedge and by a filling element, the thickness of this filling element being selected in accordance with the space to be filled. The bars 16, 17 comprise each two pointers 16^b, 17^b of which only the pointer 16^b is completely visible on the drawing and which indicate on the scale the space to be filled by the justifying elements. While the pointers 16^a, 16^b and 17^a, 17^b cover one another at the position of rest, they are spaced as soon as the wedge spacer key has been depressed once or several times, the distance between the corresponding pointers increasing at every depression of this key. This distance indicates of which thickness the filling element must be which has to be added to every wedge-spacer in order that the line may have the correct length required for the casting of the line.

There are two kinds of filling elements, the matrices of the one kind being of double the thickness of those of the other kind. The elements corresponding to these filling matrices are stored in the small sized auxiliary magazines at the left side of the main magazine. They are taken from these auxiliary magazines by hand and inserted by hand, at the beginning of the line of elements the thin filling elements being inserted at the side of the wedge spaces designed to space the words, when the end of the line is to be between the two pointers 17^a and 16^a, the thicker filling elements are to be inserted when the pointer 16^a which has advanced farthest in the left hand direction, has not yet arrived at the end of the line of elements but stands nearer to this end

than the distance between the two pointers 16^a and 17^a. If the distance between the end of the line and the pointer 16^a is greater than the distance between the pointers mentioned the line is too short and has to be 70 lengthened.

For transferring the composed line of elements into the lift a handle 31 is arranged by means of which a pair of bars 32 embracing the collector star wheel can be 75 shifted. At the left end of the front bar 32, which in Fig. 1 has been shown partly broken away, the abutment 18 is arranged against which the nose at the left end of the bar 15 bears when the maximum length of 80 the line has been reached. The handle 31 has an extension 34 by which said handle is locked in the position of rest. The abutment 18 is also locked at this occasion whereby exceeding of the maximum 85 length of the line is prevented. In order to push a line out the handle 31 is slightly turned forward and then released.

The line transferred to the lift gets onto a V-shaped toothed bar or prism 35 which 90 with the aid of a hinge 36 is suspended to a pulling strap 37 guided over a pulley 38 journaled in the upper part of the machine frame. The pulling strap is wound up on a pulley 39 on the driving cam shaft K. 95 This pulley 39 sits loosely on the cam shaft but is adapted to be connected with the same by a clutch when the lift is to be started so that, owing to the rotation of the cam shaft, the strap 37 is wound on the pulley 39 and 100 raises the lift.

The lift is securely held in its highest position by a locking hook 40 gripping under a nose 41, fixed on the lift prism 35. The locking hook 40 is fixed on an axle 42 which carries at its front end a lever 43, the lower end of which projects at 43^a on the path of the feeding bow 45. When this feeding bow arrives at the extreme right position in which all the elements have moved away from the prism 35 it strikes against the end of lever 43 and makes this lever oscillate so that the locking hook 40 fixed on the same releases the nose 41, whereupon the lift descends by gravity into the position for receiving a line of elements. At this movement of the distributing lift a parallel guiding is ensured by two pinions 47, 48 keyed 105 on an axle 46 connected with the prism 35 which pinions gear with racks 49, 50. As the pinions can rotate only through equal angles the distributing prism cannot incline and is guided parallel to itself down to the lowest position. In order to ensure that the lift prism 35 hangs down always vertically and that the elements do not come in contact with the machine frame when the lift prism is being lifted a special guide roller 51 is arranged at the left of the prism, said roller running in a groove of the frame and se- 110

cures the prism in the upper position and in the lower inclined position necessary for receiving the elements.

When the collector carriage is being transferred into the lift, the nose 123 of the collector carriage 12 strikes against the end 124 of a lever 125 and makes this lever oscillate to the left. The lever 125 pivots around a neck screw 126 fixed in the machine frame. A link 127 is arranged on the lever 125 and embraces with its slit end 129 a stud 130 fixed on the lower end of the clutch lever 131. This coupling lever is composed of two parts which are connected 15 with one another by suitable screws and washers of convenient thickness. It embraces at its upper part at 132 a bushing 134 having an annular groove and mounted on the cam shaft K. This bushing is movable in axial direction on the cam shaft K but connected by key and groove with this shaft so that it participates in the rotation of said shaft.

Two rollers 135 mounted on the enlarged part 132 of the clutch lever 131 so that they can be easily rotated are adapted to move with some play in the annular groove but draw the bushing 134 along to the right or left when the coupling lever executes greater movements.

At the movement to the right a cone 136 connected with the bushing 134 is pressed into a conical cavity of the lift pulley 39 and presses the same against a lift roller 52 and this roller against a disk 63 rigidly connected with the cam shaft K. A solid coupling between the two lift rollers 52 and 39, on the one hand and the cam shaft K, on the other hand is thus produced so that the lift rollers must rotate with the continuously rotating cam shaft, the strap 37 winding up on the roller or pulley 39 which makes the lift prism 35 ascend. The movement of lever 131 is produced in the following manner. At the movement to the left of the lower end of this lever the upper end of the same bears at first against a locking hook 138 which engages in front of a locking piece 139 fixed between the two parts of the clutch lever. The entire lever 131 executes consequently an oscillation to the left. A link 140 which embraces the stud 141 of the clutch lever is also pushed to the left and drives on its part the lower end of an elbow lever 142 which pivots around a pin 143. At the horizontal end of this elbow lever the locking hook 138 is arranged. At the oscillation of the elbow lever the locking hook 138 moves downward and slides off the locking piece 139. Before this occurs a toggle lever 145, 146 pivotally connected on the one hand at 147 with the lever 131 and on the other hand at 148 with the machine frame has been oscillated so far that it is stretched. A pull spring 149 is further put

under tension at this movement and a stud 150 slides in a slot guide piece 151 at first to the left. If now the locking hook 138 releases the other end of lever 131 the pull spring 149 tends to pull the lever 131 again 70 to the right at which occasion the toggle lever 145, 146 which had been stretched, is bent in downward direction instead of in upward direction owing to the action of the weight of rod 152 which presses upon the stud which connects the two levers 145, 146. This bending which is only very slight serves to prevent for the moment the bending of the toggle lever in upward direction. As, consequently, the lever 131 and its stud 147 cannot move to the right it is oscillated by the action of spring 149 around this stud. At this occasion the rollers 135 come in contact with the right side of the annular groove of bushing 134 and bring the cone 136, under the action of spring 149, in engagement with the conical cavity of the roller 39 effecting in this manner the above described clutching of the lift rollers 39 and 52 on the driving cam shaft K so that the lift prism 35 is raised. As soon as this prism arrives at the upper position serving for the delivery of the elements it strikes against the surface 153 of an abutment lever 154 which is pivotally mounted on a neck screw in the rear side of the machine frame and has another arm 155 with which the rod 152 is hingedly connected with the aid of a neck screw. The lever 154, 155 is thus pivoted around the neck screw, not visible on the drawing, and the rod 152 is slightly raised for such a distance that the toggle lever 145, 146, the middle stud 157 of which engages with a slit in the rod 152, is bent in upward direction. As this bending is not limited by any stop the spring 149 pulls the lever 131 farther and brings at first the lower end of the same back to the position of rest, the movement of stud 150 having previously been stopped by the end of 100 the slot in the guide piece 151. In consequence of the continued oscillation of the lever pivoting around the stud 150 the upper end of said lever swings to the left and engages behind the locking hook 138, 110 the lower end swinging to the right and returning the lever 131 into the position of rest. At this occasion the coupling of the winding up rollers with the cam shaft is disengaged by the pulling back of bushing 120 134 into the position of rest.

The winding up roller 52 serves for pulling back the feeding slide 45 by means of a string attached, on the one hand, to said roller 52 and, on the other hand, to said 125 slide 45 the repeatedly bent end of which feeding slide carries a plate 53 which, by the action of a spring, is pressed against the left end of the line of elements to be distributed. The important part of the 130

feeding slide 45 consists of a rod of round steel the right hand end of which is fixed in a carriage 64. This carriage has rollers 55, 55^a running on a rail 56 (Fig. 2) and it is pulled to the right, through the intermediary of a string 56^a guided over a pulley 57, from the spiral spring on the spring barrel 58. The right hand end of the distributing slide 45 with the plate 53 controlled by 10 said spring feeds the line of elements to a separating slide 62 which, through the intermediary of a cam disk 63 keyed on the driving shaft K, conveys the line in the well known manner to the V-shaped toothed distributing bar by pushing the same in the distributing worms.

The feeling mechanism which serves for adjusting the punches built into the distributing mechanism is, partly diagrammatically in enlarged scale, shown in Figs. 4 and 20 6. The guiding of the elements is effected by an upper pair of spindles 59 and by a lower pair of spindles 60. The spindles 60 of the lower pair are interrupted at the 25 point at which the feeling levers 76 of the feeling mechanism bear against them from either side. In the gap thus formed a short auxiliary spindle 61 is arranged, which is situated under the spindles 60 and designed 30 to seize the nose y on the lower edge of the element h in order to secure the conveying of the element. For the feeling the travelling elements must be stopped a moment. With this object in view the conveying spindles 59, 61 have at one point an irregular 35 thread, the irregularity being of such kind that the thread ascends at first more rapidly at b than the normal scope whereon follows a short stretch without pitch, at c, and then 40 a stretch of more pronounced pitch d which merges into the normal thread.

One of the spindles of the lower pair might be suppressed the remaining three spindles, two upper and one lower spindle, 45 being sufficient for the secure guiding of the elements.

The feeling mechanism might be arranged in front of the distributing mechanism. In this case a separate separating device is required and the circulating elements must be 50 of special construction. The short stop of the element takes place in this case directly after the separating which may be executed in horizontal or in vertical direction. In 55 Figs. 5 and 5^a an arrangement of this type is shown for separating in horizontal direction.

When the feeling mechanism is built into 60 the guiding for the distributing spindles (Figs. 4 and 6) the feeling proceeds in the following manner:—The elements arrive at the feeling position at c, raised by the separating slide 62 into the path of the distributing worms, where they are stopped 65 for a moment. This arrest is utilized for

feeling off the elements, which have suitable marks, by sixteen feeling levers 76 and to transmit by two of these feeling levers to a punching mechanism the effect produced by two marks. The proceeding is illustrated 70 in Figs. 1, 4, 6, 7 and 8. Fig. 8 is a plan view of Fig. 7. The feeling levers are elbow levers pivotally mounted on an axle 79. The longer end of each feeling lever 76 has a tooth 77, the other end forming a knife-edge 80. This knife edge engages at the 75 feeling off of the element with an incision of said element whereby the longer end of the elbow lever is forced to execute a corresponding movement. Each element has two 80 incisions at special points characteristic for the element. Of the sixteen feeling levers 76 the knife edges 80 of two of these levers will at the feeling off engage with the 85 incisions of one element so that the other end of these feeling levers having the tooth 77 will execute a movement in upward or downward direction.

The movement of the feeling lever 76, at the feeling off of an element, produced by 90 the engagement of the knife edge 80 with an incision of the element is transmitted by the tooth 77 to an intermediate element 78 situated above or below said tooth, said intermediate element being thus brought into 95 the path of a beating frame 81. The spring controlled feeling levers 76 are held at their longer arms by guide plates 82, 83 (Fig. 2). The guide plates are operated by two-armed 100 levers 84, 85 pivotally mounted on an axle 86, 87 and the guide plates are connected with the longer arm of said lever. The short arms of levers 84, 85 carry rollers 88, 89 and are controlled by cams 93, 94. The guide plates are connected at the upper part with 105 one-armed levers 90, 91 adapted to pivot around an axle 92. At a movement of the levers 85—90 or 84—91 caused by the cam disks 93, 94 a parallel displacement of the 110 guide plates takes place. The punching mechanism is shown in Figs. 7 and 8.

The punches 95 are connected with the intermediate elements 78 by a joint. The mutual positions of the punches correspond 115 with the perforations to be punched in the registering strip. The intermediate elements 78 are elbow levers on the short arms of which springs 96 act. Owing to the action of these springs the intermediate elements 78 are constantly pulled against the teeth 77. Controlled by the cam disks 93, 94 the guide plates 82, 83 release the feeling levers 76 at a predetermined moment so that 120 the feeling off of the element may take place. The feeling transmitted by the tooth to the intermediate element 78 brings for every element two of the intermediate elements in the path of the beating frame 81. The 125 beating frame 81 is advanced by the lever 97 and drives at i the adjusted punches 130

through the paper strip 105. The lever 97 pivots around the pin 98 and it is driven itself by a cam disk 106 from the cam shaft. The lever 99 is also operated from the driving cam shaft K through the intermediary of a cam disk 171. Lever 99 pivots around stud 100 and it is connected with a link 101 having feed-teeth 102 at its other end. The feed teeth 102 engage with the feed wheel 103 which is rigidly connected with the rubber roll 104 required for conveying the paper strip. After the punching the link 101, operated from the lever 99, makes the feed wheel 103 rotate through one step. At the same time the paper strip 105, moved by the rubber roll 104 and pressed by this roll 104 against the roll 104^a, is conveyed to the new punching position.

If no elements should be passing through the feeding mechanism a device enters into function which has for its object to throw out of gear the feeding of the paper strip and the movement of the beating frame. This device shown in Figs. 9 and 10 consists of an elbow lever 206 the end 207 of which has the shape of a rectangular plate, said lever being pivotable on an axle 208. One of the edges of the other end of lever 206 is bent at right angles perpendicularly to the lever and radially with regard to the cam shaft K and has a surface 170 inclined with regard to the cam shaft. A lever 209 is further pivotally mounted on the axle 208 and carries at its end a roller 210 running on the circumference of a cam disk 158 keyed on the cam shaft K. The levers 206, 209 are pulled towards one another by the action of spring 159. A hub 160 keyed on cam shaft K carries a fork 161 constructed after the manner of the well known crown-couplings and mounted on a pin 162. This fork 161 carries a roller 163, adapted to rotate around the stud 164, and a clutch dog 165 designed to come in engagement with the opposite tooth 166 of disk 106.

At every revolution of the cam shaft K the lever 209 is depressed and the lever 206 connected with it by spring 159 oscillates to the right as the spring 159 is stronger than the spring 167 of the lever 206. If there is no element to be felt off, the ends 168, 169 of the feeling levers 76 adopt the positions indicated in Fig. 9 in dotted lines. The plate 207 of lever 206 penetrates consequently between the feeling levers 76, so that the other end of lever 206 with the inclined surface 170 is brought in the path of the roller 163. The roller runs consequently up this inclined plane 170 lifts off the fork 161 and disengages at the same time the coupling tooth 165 so that the cam disks 106 and 171 are uncoupled. The two levers 97 and 99 (Figs. 7 and 8) which effect the movement of the beating frame 81 and the feeding of the paper strip are in this manner thrown

out of gear for one revolution. When an element is being felt off the plate 154 bears against the ends of levers 76 so that the inclined surface (see Fig. 9) shown at 170^a in dot and dash lines, does not get in the path 70 of the roller 163 and the coupling is not disengaged.

When the feeling off takes place before the elements get into the distributing spindles 59, 60 a separate separating device is required as shown in Figs. 5 and 5^a, in which the elements standing in front of the distributing slide 45 are elastically pressed against the wall 65. On this wall 65 two ribs 66 are arranged which engage with corresponding grooves of the elements. Owing to the grooves which are of different depths in accordance with the different thicknesses of the elements which come in engagement with the ribs 66 it is ensured that the back 85 of the elements is always in the same plane and it is consequently impossible that more than one element can be separated at the same time. The separating slide 67 is hingedly connected at one end with a two-armed lever 68 pivotally mounted on a pin 69. At the other end of the lever 68 a roller 70 is fixed which slides on a crank disk 71 and is raised once at every revolution during a part revolution of 90° of the crank 90 disk. By this raising of the roller 70 the slide 67 is shifted through the intermediary of the lever 68 in lateral direction towards the element and pushes the same in front of the distributing slide 45^a into the position indicated by f. The distributing slide 45^a controlled by a crank disk 72 brings the elements after a half revolution of the crank disk 72 into the feeling off position designated by g, the element being 105 pushed at the same time onto the distributing prism. In order to give the element a sufficiently secure hold in the feeling off position g for the feeling off of the marks (signatures) and to ensure the same against 110 toppling a lever 74 is provided which through the action of the spring 74^a is pressed elastically against the lower end of the element and participates in the movements of the distributing slide 45^a and of 115 the element when they are moving into the feeling off position g. After the element has been felt off the lever 74 which is fixed on a pivotable axle 76 adapted to be shifted in longitudinal direction and pressed by 120 the action of a blade spring 78 against the crank disk 75, is lowered. The axle 76 of the lever 74 is journaled at each end in one guide plate 79 which have each a bearing slot, this axle 76 being thus adapted to participate in the displacements of the lever 74. Only one of the guide plates 79 is visible in 125 Fig. 5^a. After the lever 74 has been lowered the element continues to advance in the direction in which it has started to move until, 130

arrived at the position *n*, it is gripped by the conveying worms. The continued movement of the element is controlled by the further rotation of the cam disk 72 and by the action on the distributing slide 45^a resulting from it. The controlling of the device starting from the shaft 73 on which the cam disks 71, 72, 75 are keyed, proceeds as follows:—At the first quarter revolution the separating slide 67 brings the element into the position *f*. At the second quarter revolution (90°) the element is brought by the distributing slide 45^a into the position *g*, the lever 74 being at the same time securely held by the cam 75. At the third quarter revolution the element is at rest, whereupon at the beginning of the last quarter of the revolution the lever 74 is at first depressed whereupon the element is delivered by the distributing slide 45^a to the distributing spindles. When elements pass through the punching mechanism which have feeling marks on their surfaces the mechanism shown in Figs. 13, 14, 15, 16 is necessary by means of which elements can be felt off which have holes in the required combinations.

Fig. 13 shows this mechanism viewed from the right hand side of the machine.

Fig. 14 is a plan view of Fig. 13,

Fig. 15 is a front elevation of Fig. 13.

Fig. 16 illustrates the transmission to the punching mechanism.

The line delivered from the lift 35 to be distributed is pressed in the distributing box 177 by the feeding slide 197 through the action of the spring controlling this slide (said spring being not visible on the drawing) against the buffer wall 178. A number of feeler needles 181 project through the buffer wall 178. These needles 181 are adapted to move in the box 179 and they are held in the zero position shown in Fig. 14 by the action of springs 180. The elements have holes through which the feeler needles penetrate when the elements are being pressed by the feeding slide 197 against the buffer wall 178.

Only at those points at which the element is intended to act by its characteristic mark on the feeler needles there are no holes so that the corresponding feeler needles 181 are pushed back when the element is being pressed against the buffer wall.

The two feeler needles 181 which are operated by the solid parts between two holes of the element, are thus pushed back and strike with their ends 182 against two of the two-armed levers of the groups 183, 184. The two-armed levers of the groups 183, 184 are pivotally mounted on the pins 185, 186 and connected at their other ends with the elbow levers 187 (Figs. 13 and 16). The elbow levers 187 pivot around the axle 188 and their noses 189 bear on the intermedi-

ate elements 78 of the punching mechanism mentioned before. If two of the levers 183, 184 are pushed back by the feeler needles 181 the other end of said levers swings in opposite direction and draws along the elbow lever 187 hingedly connected with the same.

The nose 189 of this elbow lever 187 exerts a pressure on the intermediate element 78 so that this element is brought in the path of the beating frame 81. This beating frame 81 is thrown forward by a cam disk on the cam shaft K at the predetermined moment and draws along the intermediate elements 78 which, as shown in Fig. 16 in dash lines, are in front of it and also the punches 95 connected with these intermediate elements so that the paper strip is being punched. When the beating frame 81 has arrived again at the position of rest the intermediate element 78 is removed by the action of its spring 96 from the range of the beating frame, the elbow lever 187 and the levers 183, 184 being also returned to the initial position. In order to make possible on the one hand this returning to the initial position and on the other hand the separation of the element which after the feeling off must be conveyed to the distributing spindles, the buffer wall 178 is pushed back together with the element in the direction towards the feeding slide 197. This occurs shortly before the beating frame has arrived at its position of rest. The pushing back of the buffer wall 178 is effected through the intermediary of a lever 191 and of a combined cam disk 190, the latter serving at the same time for controlling the separating and the feeding to the distributing spindles.

The two-armed lever 191 is fork-shaped at one end and pivots around the axle 193 and it comes in contact at 192 with the buffer wall 178. A roller 202 is rotatably mounted on the other end of the lever 191. The cam disk 190 is keyed on the axle 194 this axle being connected with the distributing spindle 60 by toothed wheel transmission gear. At every rotation of the distributing spindle 60 the axle 194 executes also a revolution and the cam 190^a on the cam disk 190 presses the lever 191 against the buffer wall.

Owing to the buffer wall being pushed back the element 195 which has just been felt off is released from the feeler needles 181 which have penetrated into the same and it is now free to be brought by the separating slide 196 in the path of the distributing slide 197^a which delivers it to the distributing spindles. The separating slide 196 is operated by the lever 198 which pivots around the axle 199. At the other end of lever 198 a roller 200 is rotatably mounted. This roller 200 rests on the cam disk 190 so that it is advanced by this disk at every revolution of the same at a predetermined

moment, the other end of the lever 198 which is hingedly connected with the separating slide 196 shifting this slide to the left, as seen in Fig. 13, whereby the element 5 195 is separated from the other elements of the line.

As the elements are of different thickness a groove is milled into the thicker elements in order to prevent several elements from 10 being separated at the same time. This groove is of such depth that the remaining part of the element at this point is equal to the thickness of the next thinnest of the elements. A nose 201 sliding through this 15 groove prevents the separation of more than one element from the line. This arrangement, known per se, is applied in the form of construction shown in the direction of the broad side of the element, it being otherwise normally applied in the longitudinal 20 direction. The distributing slide 197^a is moved in the direction towards the distributing spindles 59, 60 by a two-armed lever 203 which is also controlled from the 25 combined cam disk 190 and pivots around an axle 204 as said lever 203 is hingedly connected at 205 with said slide 197^a. The separated element 195 which has been brought in the path of distributing slide 30 197^a, shown in Fig. 14 at 195^a in dot lines, is thus conveyed to the distributing spindles which grip the same and convey it into the channels of the magazine.

The driving cam shaft K driven from a 35 motor by means of a grooved cord pulley 171 (Fig. 1) serves for driving the machine. The different cam disks, clutches and lifting rolls are arranged on the left part of this shaft and on its right hand end a spur wheel 40 172 is keyed which drives by an intermediate wheel 173 the toothed wheels 174, 175, 176 of the distributing spindles.

In the form of construction of the machine illustrated on the accompanying 45 drawings a shifting is arranged by which the circulation of separate elements for the capital letters is avoided.

The shifting is effected in the following manner:—By the depression of the key *a* 50 (Fig. 2) the locking hook 2 is disengaged by the nose 108 on lever 107. When the shift key *k* is being depressed the lever 109 of this key is oscillated around the shaft 110. The other end of this key lever 109, 55 which is an elbow lever, acts upon an intermediate lever 111 pivotally mounted on a pin 112. The other end of the intermediate lever 111 is pivotally connected to a frame 113 extending over the entire length of the 60 key board and oscillably mounted on the shaft 114. With this frame 113 a second frame 115 oscillably is connected which is pivotally mounted on a shaft 116. A dog 65 117 on this frame 115 is connected by a link 118 with one of the locking hooks 2 which

operate the releasing mechanism for the elements. At the depression of any of the normal keys *a* the point 1 of key *a* can freely move. When however the shift key marked 1 has been previously depressed and is held 70 depressed the frame 115 is pushed against the point 1 of the key levers and, when now one of the normal keys is depressed, the locking hook 2 is disengaged through the intermediary of the frame 115, of the dog 75 117 and of the link 118.

The elements to be used in the machine are shown in Figs. 11 and 12. Fig. 11 shows an element to be used when the feeling mechanism is built into the spindle guide of the 80 distributing mechanism. This element has at its foot end a rectangular or triangular projection *y* to be gripped by the auxiliary distributing spindles and further for the separating slot for the separating and for 85 the raising into the path of the spindles, such slots being known from the composing machine matrices.

Fig. 12 shows an element to be used in connection with a special separating arrangement in front of the guiding for the distributing spindles. It has transverse grooves *r*, *s* corresponding with the ribs on 90 the buffer wall of the separating device.

Fig. 17 shows an element for surface 95 feeling by hole constructions. *v* and *w* are the operative points of the element and *x* is the groove required for the separating.

Fig. 18 shows an element which by means 100 of ribs *z*, obtained by grooves cut into the surface, acts upon the feelers.

Fig. 18^a is a side elevation of Fig. 18 on larger scale.

The elements shown in Figs. 11 and 12 may be provided with edge marks in the form of projections instead of with incisions in the edges. In this case another mode of operation is required for the feeling off of the elements. The elements do in this case not work passively, in being felt off by the feelers of the adjusting mechanism for the punching mechanism dropping into the incisions of the edges, but actively in pushing away the feelers by their projections on the edges.

In all elements the type taken for the composer is preferably arranged at *t*. The elements which represent wedge spacers and those which have merely the signification of signals for the various purposes of the shifting and are called filling elements may be of any suitable shape.

We claim:—

1. In machines for producing the controlling bands for operating band-controlled type-setting machines or band controlled matrix-setting and line-casting machines the combination, of a punching device containing a plurality of punches, punch operating means for operating said punches, a plu- 125 130

connecting means for operatively connecting said key board to said releasing means for operating the latter by means of said key board, separating means for separating an assembled line of elements into single elements, line-transferring means for transferring an assembled line of elements from said assembling means to said separating means, means for transferring the separated elements into said distributing means, said elements thereby passing said punch controlling means and causing one or more of the latter to be properly actuated, and means for controlling the length of the lines of elements.

4. In machines for producing the controlling bands for operating band-controlled type-setting machines or band controlled matrix-setting and line-casting machines the combination, of a punching device containing a plurality of punches, punch operating means for operating said punches, a plurality of punch controlling means for controlling the operation of said punches by said operating means and when properly actuated causing a punch to be operated, punch controlling actuating means for actuating said punch controlling means consisting of a double system of feeling levers, a plurality of circulating elements adapted to circulate in the machine each element representing a character or sign or punctuation mark the thickness of each of said elements being in proportion to the width of the character or sign or punctuation mark represented by the element, in the longitudinal edges of each element provided with cavities for controlling the actuation of one or more of said punch controlling actuating means, a plurality of magazines each adapted to receive all of said elements representing the same character or sign or punctuation mark, distributing means for distributing said elements into said magazines said distributing means consisting of two groups of grooved distributing spindles, one group situated above the other group the spindles of the lower group being interrupted at the part where said feeling levers engage with the grooves of said spindles, an auxiliary distributing spindle under the gap in said lower distributing spindles for guiding said elements the thread of said upper distributing spindles and said auxiliary spindle being partly without slope, releasing means for releasing said elements from said magazines assembling means for assembling said elements after they have been released from said magazines into lines each line of elements representing a line of types consisting of characters signs and punctuation marks to be printed, a key board, operatively connecting means for operatively connecting said key board to said releasing means for operating the latter by means of said key board, separating means for separating an assembled line of elements into single elements, line-transferring means

for transferring an assembled line of elements from said assembling means to said separating means, means for transferring the separated elements into said distributing means, said elements thereby passing said punch controlling means and causing one or more of the latter to be properly actuated, and means for controlling the length of the lines of elements.

5. In machines for producing the controlling bands for operating band-controlled type-setting machines or band controlled matrix-setting and line-casting machines the combination, of a punching device containing a plurality of punches, punch operating means for operating said punches, a plurality of punch controlling means for controlling the operation of said punches by said operating means and when properly actuated causing a punch to be operated, punch controlling actuating means for actuating said punch controlling means consisting of a double system of feeling levers, a plurality of circulating elements adapted to circulate in the machine each element representing a character or sign or punctuation mark the thickness of each of said elements being in proportion to the width of the character or sign or punctuation mark represented by the element, in the longitudinal edges of each element provided with cavities for controlling the actuation of one or more of said punch controlling actuating means, a plurality of magazines each adapted to receive all of said elements representing the same character or sign or punctuation mark, distributing means for distributing said elements into said magazines, said distributing means consisting of two groups of grooved distributing spindles, one group situated above the other group the spindles of the lower group being interrupted at the part where said feeling levers engage with the grooves of said spindles, an auxiliary distributing spindle under the gap in said lower distributing spindles for guiding said elements the thread of said upper distributing spindles and said auxiliary spindle being partly without slope, releasing means for releasing said elements from said magazines assembling means for assembling said elements after they have been released from said magazines into lines each line of elements representing a line of types consisting of characters signs and punctuation marks to be printed, a key board, operatively connecting means for operatively connecting said key board to said releasing means for operating the latter by means of said key board, separating means for separating an assembled line of elements into single elements, line-transferring means for transferring an assembled line of elements from said assembling means to said separating means, means for transferring the separated elements into

said distributing means, said elements thereby passing said punch controlling means and causing one or more of the latter to be properly actuated, and means for controlling the 5 length of the lines of elements.

6. In machines for producing the controlling bands for operating band-controlled type-setting machines or band controlled matrix-setting and line-casting machines the 10 combination, of a punching device containing a plurality of punches, punch operating means for operating said punches, a plurality of punch controlling means for controlling the operation of said punches by said 15 operating means and when properly actuated causing a punch to be operated, punch controlling actuating means for actuating said punch controlling means consisting of feeling levers, a plurality of circulating ele- 20 ments adapted to circulate in the machine each element representing a character or sign or punctuation mark the thickness of each of said elements being in proportion to the width of the character or sign or punctuation 25 mark represented by the element, projections on each element for controlling the actuation of one or more of said feeling levers, a plurality of magazines each adapted to receive all of said elements representing the same character or sign or punctuation 30 mark, distributing means for distributing said elements into said magazines, releasing means for releasing said elements from said magazines, assembling means for assembling said elements after they have been released from said magazines into lines each line of elements representing a line of types consisting of characters, signs and punctuation marks to be printed, a key board, operatively connecting means for operatively connecting said key board to said releasing means for operating the latter by means of said key board, separating means for separating an assembled line of elements 35 into single elements, line-transferring means for transferring an assembled line of elements from said assembled means to said separating means, means for transferring the separated elements into said distributing 40 means, said elements thereby passing said punch controlling means and causing one or more of the latter to be properly actuated, and means for controlling the length of the lines of elements.
- 45 7. In machines for producing the controlling bands for operating band-controlled type-setting machines or band controlled matrix-setting and line-casting machines the combination, of a punching device containing a plurality of punches, punch operating means for operating said punches, a plurality 50 of punch controlling means for controlling the operation of said punches by said operating means and when properly actuated causing a punch to be operated, punch controlling actuating means for actuating said punch controlling means, a plurality of circulating elements adapted to circulate in the machine each element representing a character or sign or punctuation mark the thickness of each of said elements being in proportion to the width of the character or sign or punctuation 55 mark represented by the element, means on each element for controlling the actuation of one or more of said punch controlling actuating means, a plurality of magazines each adapted to receive all

controlling actuating means for actuating said punch controlling means consisting of feeling levers, a plurality of circulating elements adapted to circulate in the machine each element representing a character or 70 sign or punctuation mark the thickness of each of said elements being in proportion to the width of the character or sign or punctuation mark represented by the element, projections on each element for controlling the actuation of one or more of said feeling levers, a plurality of magazines each adapted to receive all of said elements representing the same character or sign or punctuation 75 mark, distributing means for distributing said elements into said magazines, releasing means for releasing said elements from said magazines, assembling means for assembling said elements after they have been released from said magazines into lines each line of elements representing a line of types consisting of characters, signs and punctuation marks to be printed, a key board, operatively connecting means for operatively connecting said key board to said releasing means for operating the latter by means of said key board, separating means for separating an assembled line of elements into single elements said separating means consisting of a separating box, an abutment on said box, ribs on said abutment on which said elements are guided in accordance with their thickness, line-transferring means for transferring an assembled line of elements from said assembling means to said separating 90 means, means for transferring the separated elements into said distributing means, said elements thereby passing said punch controlling means and causing one or more of the latter to be properly actuated, and means for controlling the length of the lines of elements.

8. In machines for producing the controlling bands for operating band-controlled type-setting machines or band controlled matrix-setting and line-casting machines the combination, of a punching device containing a plurality of punches, punch operating means for operating said punches, a plurality of punch controlling means for controlling the operation of said punches by said operating means and when properly actuated causing a punch to be operated, punch controlling actuating means for actuating said punch controlling means, a plurality of circulating elements adapted to circulate in the machine each element representing a character or sign or punctuation mark the thickness of each of said elements being in proportion to the width of the character or sign or punctuation mark represented by the element, means on each element for controlling the actuation of one or more of said punch controlling actuating means, a plurality of magazines each adapted to receive all 100

- of said elements representing the same character or sign or punctuation mark, distributing means for distributing said elements into said magazines, releasing means 5 for releasing said elements from said magazines, assembling means for assembling said elements after they have been released from said magazines into lines each line of elements representing a line of types consisting 10 of characters, signs and punctuation marks to be printed, a key board, operatively connecting means for operatively connecting said key board to said releasing means for operating the latter by means of said key 15 board, separating means for separating an assembled line of elements into single elements said separating means consisting of the separating slide, line-transferring means for transferring an assembled line of elements 20 from said assembling means to said separating means said transferring means consisting of an elevating slide, means for transferring the separated elements into said distributing means, said elements thereby 25 passing said punch controlling means and causing one or more of the latter to be properly actuated, and means for controlling the length of the lines of elements, said separating slide, elevating slide and distributing 30 means being arranged with regard to one another so that the separating of the elements from the composed line, the conveying of the elements along said punch controlling actuating means and to said distributing 35 means are carried.
9. In machines for producing the controlling bands for operating band-controlled type-setting machines or band controlled matrix-setting and line-casting machines the 40 combination, of a punching device containing a plurality of punches, punch operating means for operating said punches, a plurality of punch controlling means for controlling the operation of said punches by said 45 operating means and when properly actuated causing a punch to be operated, punch controlling actuating means for actuating said punch controlling means consisting of a system of feeling needles, a plurality of 50 circulating elements adapted to circulate in the machine each element representing a character or sign or punctuation mark the thickness of each of said elements being in proportion to the width of the character or 55 sign or punctuation mark represented by the element, perforations in each element for controlling the actuation of one or more of said feeling needles adapted to engage with the corresponding perforations of said elements 60 and then to operate by their heads said punch controlling actuating means, a plurality of magazines each adapted to receive all of said elements representing the same character or sign or punctuation mark, distributing 65 means for distributing said elements into said magazines, releasing means for releasing said elements from said magazines, assembling means for assembling said elements after they have been released from said magazines into lines each line of elements representing a line of types consisting of characters, signs and punctuation signs to be printed, a key board, operatively connecting means for operatively connecting said key board to said releasing means for operating the latter by means of said key board, separating means for separating an assembled line of elements into single elements, line-transferring means for transferring an assembled line of elements from said assembling means to said separating means, means for transferring the separated elements into said distributing means, said elements thereby passing said punch controlling means and causing one or more of the latter to be properly actuated, and means for controlling the length of the lines of elements.
10. In machines for producing the controlling bands for operating band-controlled type-setting machines or band controlled matrix-setting and line-casting machines the combination, of a punching device containing a plurality of punches, punch operating means for operating said punches, a plurality of punch controlling means for controlling the operation of said punches by said operating means and when properly actuated causing a punch to be operated, punch controlling actuating means for actuating said punch controlling means, a plurality of 90 circulating elements adapted to circulate in the machine each element representing a character or sign or punctuation mark the thickness of each of said elements being in proportion to the width of the character or sign or punctuation mark represented by auxiliary elements designed to be joined with any one of said elements to form the corresponding capital letter, means on each element for controlling the actuation of one or more of said punch controlling actuating means, a plurality of magazines each adapted to receive all of said elements representing the same character or sign or punctuation mark, distributing means for distributing said elements into said magazines, releasing means for releasing said elements from said magazines, assembling means for assembling said elements after they have been released from said magazines into lines each line of elements representing a line of types consisting of characters, signs and punctuation marks to be printed, a key board, operatively connecting means for operatively connecting said key board to said releasing means for operating the latter by means of said key board, separating means for separating an assembled line of elements into single elements, line-transferring means for transferring an assembled line of elements

- ments from said assembling means to said separating means, means for transferring the separated elements into said distributing means, said elements thereby passing said 5 punch controlling means and causing one or more of the latter to be properly actuated, and means for controlling the length of the lines of elements.
11. In machines for producing the controlling bands for operating band-controlled type-setting machines or band controlled matrix-setting and line-casting machines the combination, of a punching device containing a plurality of punches, punch operating means for operating said punches, a plurality of punch controlling means for controlling the operation of said punches by said operating means and when properly actuated causing a punch to be operated, 15 punch controlling actuating means for actuating said punch controlling means, a plurality of circulating elements adapted to circulate in the machine each element representing a character or sign or punctuating 20 mark the thickness of each of said elements being in proportion to the width of the character or sign or punctuation mark represented by the filling elements to be inserted into the composed line for lengthening the 25 space to be filled and representing neither a character nor sign nor punctuation mark, so that they do not appear in print, means on each member for controlling the actuation of one or more of said punch controlling 30 actuating means, a plurality of magazines each adapted to receive all of said elements representing the same character or sign or punctuation mark, distributing means for distributing said elements into said magazines, releasing 35 means for releasing said elements from said magazines, assembling means for assembling said elements after they have been released from said magazines into lines each line of elements representing 40 zines, releasing means for releasing said elements from said magazines, assembling means for assembling said elements after they have been released from said magazines into lines each line of elements representing 45 a line of types consisting of characters, signs and punctuation marks to be printed, a key board, operatively connecting means for operatively connecting said key board to said releasing means for operating the latter by 50 means of said key board, separating means for separating an assembled line of elements into single elements, line-transferring means for transferring an assembled line of elements from said assembling means to said 55 separating means, means for transferring the separated elements into said distributing means, said elements thereby passing said punch controlling means and causing one or more of the latter to be properly actuated, 60 and means for controlling the length of the lines of elements said means consisting of an abutment, at the beginning or end of the line, of a hand fixed on said abutment, of an indicating scale for said hand, and means for lengthening the line according to the thickness of the filling elements inserted.
12. In machines for producing the controlling bands for operating band-controlled type-setting machines or band controlled matrix-setting and line-casting machines the combination, of a punching device containing a plurality of punches, punch operating means for operating said punches, a plurality of punch controlling means for controlling the operation of said punches by said operating means and when properly actuated causing a punch to be operated, punch controlling actuating means for actuating said punch controlling means, a plurality of circulating elements adapted to circulate in the machine, each element representing a character or sign or punctuation mark the thickness of each of said elements being in proportion to the width of the character or sign or punctuation mark represented by the element, means on each element for controlling the actuation of one or more of said punch controlling actuating means, transmitting means connected with said punching device so that for each element a combination of perforations is punched in a paper strip, means for feeding said paper strip after each punching operation for the length of one group of perforations, a plurality of magazines each adapted to receive all of said elements representing the same character or sign or punctuation mark, distributing means for distributing said elements into said magazines, releasing 90 means for releasing said elements from said magazines, assembling means for assembling said elements after they have been released from said magazines into lines each line of elements representing a line of types consisting of characters, signs and punctuation marks to be printed, a key board, operatively connecting means for operatively connecting said key board to said releasing means for operating the latter by means of said key board, separating means for separating an assembled line of elements into single elements, line-transferring means for transferring an assembled line of elements from said assembling means to said separating means, means for transferring the separated elements into said distributing means, said elements thereby passing said punch controlling means and causing one or more of the latter to be properly actuated, and means for controlling the length of the lines of elements.
13. In machines for producing the controlling bands for operating band-controlled type-setting machines or band controlled matrix-setting and line-casting machines the combination, of a punching device containing a plurality of punches, punch operating means for operating said punches, a

- plurality of punch controlling means for controlling the operation of said punches by said operating means and when properly actuated causing a punch to be operated, 5 punch controlling actuating means for actuating said punch controlling means, a plurality of circulating elements adapted to circulate in the machine each element representing a character or sign or punctuation 10 mark the thickness of each of said elements being in proportion to the width of the character or sign or punctuation mark represented by the filling elements to be inserted into the composed line for lengthening 15 ing the space to be filled and representing neither a character nor sign nor punctuation so that they do not appear in print, means on each element for controlling the actuation of one or more of said punch controlling 20 actuating means, a plurality of magazines each adapted to receive all of said elements representing the same character or sign or punctuation mark, distributing means for distributing said elements into said magazines 25 releasing means for releasing said elements from said magazines, assembling means for assembling said elements after they have been released from said magazines into lines each line of elements representing 30 a line of types consisting of characters, signs and punctuation marks to be printed, a key board, operatively connecting means for operatively connecting said key board to said releasing means for operating 35 the latter by means of said key board, separating means for separating an assembled line of elements into single elements, line-transferring means for transferring an assembled line of elements from said assem- 40 blings means to said separating means, means for transferring the separated elements into said distributing means, said elements thereby passing said punch controlling means and causing one or more of the latter to be properly actuated, means for controlling the length of the lines of elements said means consisting of an abutment at the beginning or end of the line, of a hand fixed on said abutment, of an indicating scale for said hand, and means for lengthening the line according to the thickness of the filling elements inserted, a coupling mechanism between said punch controlling actuating means and said punch 45 controlling means, and means for uncoupling said coupling mechanism when a filling element passes along.
14. In machines for producing the controlling bands for operating band-controlled type-setting machines or band controlled matrix-setting and line-casting machines the combination, of a punching device containing a plurality of punches, punch operating means for operating said punches, a plurality of punch controlling means for controlling the operation of said punches by said operating means and when properly actuated causing a punch to be operated, punch 50 controlling the operation of said punches by said operating means and when properly actuated causing a punch to be operated, punch controlling actuating means for actuating said punch controlling means consisting of a double system of feeling levers, a plurality of circulating elements adapted to circulate in the machine each element representing a character or sign or punctuation 55 mark the thickness of each of said elements being in proportion to the width of the character or sign or punctuation mark represented by the element, cavities in the longitudinal edges of each element for controlling the actuation of one or more of said punch controlling actuating means, a plurality of magazines each adapted to receive all of said elements representing the same character or sign or punctuation mark distributing means for distributing said elements into said magazines said distributing means consisting of two groups of grooved distributing spindles, one group situated above the other group the spindles of the lower group being interrupted at the part 60 where said feeling levers engage with the grooves of said spindles, an auxiliary distributing spindle under the gap in said lower distributing spindle for guiding said elements, a projection on the foot of each element designed to engage with the guide groove of said auxiliary distributing spindle, releasing means for releasing said elements from said magazines, assembling means for assembling said elements after they have been released from said magazines into lines each line of elements representing 65 a line of types consisting of characters, signs and punctuation marks to be printed, a key board, operatively connecting means for operatively connecting said key board to said releasing means for operating the latter by means of said keyboard, separating means for separating an assembled line of elements into single elements, line-transferring means 70 for transferring an assembled line of elements from said assembling means to said separating means, means for transferring the separated elements into said distributing means, said elements thereby passing said punch controlling means and causing one or more of the latter to be properly actuated, and means for controlling the length of the lines of elements.
15. In machines for producing the controlling bands for operating band-controlled type-setting machines or band controlled matrix-setting and line-casting machines the combination, of a punching device containing a plurality of punches, punch operating means for operating said punches, a plurality of punch controlling means for controlling the operation of said punches by said operating means and when properly actuated causing a punch to be operated, punch 75 80 85 90 95 100 105 110 115 120 125 130

controlling actuating means for actuating said punch controlling means, a plurality of circulating elements adapted to circulate in the machine each element representing a character or sign or punctuation mark the thickness of each of said elements being in proportion to the width of the character or sign or punctuation mark represented by the element, means on each element for controlling the actuation of one or more of said punch controlling actuating means, said means consisting in grooves extending in the direction of separation and being of different depth in the several elements so that the solid parts of all elements at the back of the grooves are of equal thickness and correspond with the thickness of the thinnest element, a plurality of magazines each adapted to receive all of said elements representing the same character or sign or punctuation mark, distributing means for distributing said elements into said magazines, releasing means for releasing said elements from said magazines, assembling means for assembling said elements after they have been released from said magazines into lines each line of elements representing a line of types consisting of characters, sign and punctuation marks to be printed, a key board, operatively connecting means for operatively connecting said key board to said releasing means for operating the latter by means of said key board, separating means for separating an assembled line of elements into single elements, line-transferring means for transferring an assembled line of elements from said assembling means to said separating means, means for transferring the separated elements into said distributing means, said elements thereby passing said punch controlling means and causing one or more of the latter to be properly actuated, and means for controlling the length of the lines of elements.

In testimony whereof we affix our signatures.

OTTO WOLTERS.
